(57) **CLAIM**

The ornamental design for a folding front sight, as shown and described.

DESCRIPTION

FIG. 1 is a perspective view of the folding front sight in accordance with the present invention;

FIG. 2 is a left side thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is another perspective view showing the folding front sight in a stowed position;

FIG. 9 is a perspective view of an alternative embodiment of the folding front sight in accordance with the present invention;

FIG. 10 is a left side thereof;

FIG. 11 is a right side view thereof;

FIG. 12 is a front view thereof;

FIG. 13 is a rear view thereof;

FIG. 14 is a top view thereof; and,

FIG. 15 is a bottom view thereof.

The elements depicted in broken line in the various figures are included for environmental purposes only, and form no part of the claimed design.
